(57) **CLAIM**

The ornamental design for a hair straightening appliance as shown and described.

DESCRIPTION

FIG. 1 is a top, side perspective view of an ornamental design for a hair straightening appliance according to the present invention;

FIG. 2 is a right side elevational view of the hair straightening appliance of FIG. 1;

FIG. 3 is a left side elevational view of the hair straightening appliance of FIG. 1;

FIG. 4 is a top plan view of the hair straightening appliance of FIG. 1;

FIG. 5 is a bottom plan view of the hair straightening appliance of FIG. 1;

FIG. 6 is a rear elevational view of the hair straightening appliance of FIG. 1; and,

FIG. 7 is a front elevational view of the hair straightening appliance of FIG. 1.

The broken lines in the figures are for the purpose of illustrating portions of the hair straightening appliance, which form no part of the claimed design.
